PROCESS FOR THE NITRATION OF
HALOBENZENESRobert I. Leib, Kirkwood, Mo., assignor to Monsanto
Chemical Company, St. Louis, Mo., a corporation of
Delaware

No Drawing. Filed Feb. 5, 1960, Ser. No. 6,859

19 Claims. (Cl. 260—646)

This invention relates to an improved process for the preparation of nitrohalobenzenes by the nitration of the corresponding halobenzene, whereby a more favorable isomer distribution is obtained.

The present methods used in the preparation of nitrochlorobenzene, for example yield a mixture of the para and ortho isomers, in which the para/ortho ratio is generally around 1.7, i.e. it contains 63% para isomer and 37% ortho isomer. Because of the current and projected demand for the para isomer, a great oversupply of the ortho isomer will result if this need for the para isomer is fulfilled by using the current methods of making nitrochlorobenzene.

It has been found that the isomer distribution in the nitrohalobenzene product is favorably influenced when the nitration of a halobenzene compound is carried out in the presence of an amine salt. The presence of even small amounts of an amine salt markedly influences the isomer distribution in a nitrohalobenzene product and this effect is still obtained when a high concentration of amine salt is employed, i.e. where 3 moles of amine salt per mole of halobenzene are used. Moreover, the amount of the desired isomer obtained when the nitration is carried out in the presence of an amine salt is greater than the amount obtained in the absence of an amine salt regardless of the nitrating agent or nitrating temperature employed.

The nitrating agents which can be employed in the process of this invention include, for example, the conventional mixed acids, i.e. mixtures of nitric acid and a dehydrating acid such as oleum or sulfuric acid, which contain from about 20% to about 60% by weight of nitric acid and from about 75% to about 35% by weight of sulfuric acid, the balance being made up by water; a mixture of ethyl nitrate and sulfuric acid, nitrogen pentoxide and other strong nitrating agents which are conventionally employed in the nitration of a halobenzene. Mixed acids containing from about 30% to about 40% by weight of nitric acid and from about 65% to about 55% by weight of sulfuric acid are preferred for the process of this invention.

The amine salts which are useful in the process of this invention are the amine salts of nitric acid or sulfuric acid or mixtures thereof. Any amine salt can be employed, however the amine salts in which the organic residue is not subject to nitration or oxidation under the nitrating conditions employed are preferred for the purposes of this invention.

Illustrative examples of amines which can be employed in the process of this invention in their nitrate or sulfate form are the primary aliphatic amines such as methylamine, ethylamine, propylamine, isopropylamine, n-hexylamine, dodecylamine, tetradecylamine, hexadecylamine, etc.; secondary aliphatic amines such as dimethylamine, diethylamine, diisopropylamine, di-2-ethylhexylamine, N-methyl-dodecylamine, N-ethyl-pentadecylamine, etc.; tertiary aliphatic amines such as trimethylamine, triethylamine, tripropylamine, tributylamine, trioctylamine, N-methyldiethylamine, N-ethyldiisopropylamine, N-pentyl-diisopropylamine, N,N-diisobutylhexylamine, etc.; the aliphatic polyamines such as 1,4-propylenediamine, 1,3-ethylenediamine, 1,2-butylenediamine, etc.; the cycloaliphatic amines such as cyclopentylamine, cyclohexylamine, 2,4-di-

2

methylcyclohexylamine, 2-methylcyclohexylamine, 4-ethylcyclohexylamine, cycloheptylamine, 4-methylcycloheptylamine, dicyclohexylamine, cyclohexane 1,3-diamine etc.; mixed aliphatic-cycloaliphatic amines such as N-ethylcyclohexylamine, N-butylcyclohexylamine, N-propylcycloheptylamine, N,N-diethylcyclohexylamine, etc.; the heterocyclic amines such as pyrrolidine, 2-methylpyrrolidine, 2-ethylpyrrolidine, 2,4-dimethyl-3-ethylpyrrolidine, 1,2,2-trimethylpyrrolidine, 3,4-dimethylpyrrolidine, pyrazole, 2-methylpyrazole, 2-ethylpyrazole, 2,5-dimethylpyrazole, 2,3,5-trimethylpyrazole, 3,5-dimethylpyrazole, imidazole, 1-ethylimidazole, 4-methylimidazole, 1,2,3-triazole, 4,5-dimethyl-1,2,3-triazole, 1,2,4-triazole, pyridine, 2-picoline, 3-picoline, 2-lutidine, parvoline, rubidine, 3-picoline, 2-piperidine, 3-piperidine, 4-piperidine, 1,2-dimethylpiperidine, 1,4-dimethylpiperidine, 2,6-trimethylpiperidine, 2-methyl-5-ethylpiperidine, morpholine, 2-methylmorpholine, triamorpholine, 2-ethylmorpholine, pyrazine, quinoline, isoquinoline, 2,4-dimethylquinoline, 4-ethylquinoline, 2,5-pyridoquinoline, 1,3-oxazole, 1,2,4-oxadiazine, 1,4,2-oxadiazine, indoloindole, 1-indeno-1,2b-pyridine, acridine, 1-methylacridine, 2-methylacridine, 1,3-dimethylacridine, 2,5-dimethylacridine, phenanthridine, 2-methylphenanthridine, 2-ethylphenanthridine, 1,3-dimethylphenanthridine, 5,6-benzoquinoline, 6,7-benzoquinoline, 7,8-benzoquinoline, 6,7-benzoisoquinoline, naphtho-2,3h-quinoline, etc.

While the amines containing an aromatic residue are generally subject to nitration, they may be used in the process of this invention if an excess of the nitrating agent is employed. Illustrative examples of amines containing an aromatic residue are, for example, aniline, naphthylaniline, phenylenediamine, 3,5-dimethylaniline, 2,3,6-triethylaniline, phenanthrylamine, mixed coal tar bases, N-methylaniline, diphenylamine, N-octylphenylamine, N-butyl-p-methoxyaniline, N-cyclohexylaniline, N-2-ethylhexylaniline, N-octylbiphenylamine, dinaphthylamine, N-methyldiphenylamine, N-butylbiphenylamine, benzylamine, phenylethylamine, 2,4-dimethylbenzylamine, 3-butylbenzylamine, 4-t-butylphenylethylamine, N,N-dimethylbenzylamine, N,N-diethylbenzylamine, N,N-dipropylbenzylamine, N-ethylbenzylamine, N-hexylbenzylamine, and their homologues and analogues.

The aforementioned amines may be further substituted by one or more substituents. Typical but not limitative of such substituents are nitro, carboxy, the halogens, such as chlorine, bromine, iodine and fluorine, and other non-reactive substituents.

The lower aliphatic amines which have a tertiary alkyl group attached to the nitrogen atom constitute a preferred class of aliphatic amines to be employed as their acid salts in the process of this invention. These amines have the following structure:

wherein R is an alkyl radical containing from 1 to 18 carbon atoms, e.g. methyl, ethyl, propyl and butyl.

The acid salts of heterocyclic amines containing a tertiary nitrogen atom also constitute a preferred class of acid salts to be employed in the process of this invention.

The acid salt can be prepared separately or it can be prepared in situ. For example, the free amine can be added to the nitration reaction medium and the amine converted to the acid salt form by the addition of a sufficient excess of nitric or sulfuric acid to tie up the free amine. Moreover, a preferred method of carrying out the process of this invention involves adding concentrated sulfuric acid to a mixture of the halobenzene and the free amine. After all of the amine has been con-

verted to the acid sulfate form, the mixed acid nitration is then started.

Effective concentrations of the amine salt in the process of this invention vary in wide ranges depending upon the result desired, in that extremely low amounts, e.g. 0.05 mole of amine salt per mole of halobenzene to be nitrated will produce the para directive effect. Moreover, as the number of amine salt groups per molecule is increased, the amount required to produce a given result is reduced proportionately. A higher para isomer concentration in the nitrohalobenzene product is achieved when the concentration of amine salt is within the range of from about 0.5 to about 2 moles per mole of halobenzene to be nitrated. It is even more preferred to employ about 1.0 mole of amine salt per mole of halobenzene to be nitrated. More than 3 moles of amine salt per mole of halobenzene to be nitrated can be employed, however no significant increase in para isomer content or yield results over that which is obtained with 1 to 2 moles.

A preferred embodiment of this invention is the process for the preparation of paranitrochlorobenzene which comprises nitrating chlorobenzene with a mixed acid comprising 30% to 35% by weight of nitric acid, 55% to 60% by weight of sulfuric acid and 15% to 5% by weight of water, in the presence of a sulfate salt of a lower aliphatic amine having a tertiary alkyl group attached to the nitrogen atom thereof. A further preferred embodiment involves the use of a sulfate salt of a heterocyclic amine having a tertiary nitrogen atom.

Those skilled in the art will recognize that this invention is not limited to specific reaction temperatures since this process can be carried out at a tempearture of from -30° C. to 100° C. or more. A reaction temperature of -30° C. can be maintained, for example, by employing a cooling bath comprising a slurry of solid carbon dioxide in acetone and using chloroform as a reaction diluent. As will be appreciated, the rate of reaction at temperatures of from -30° C. to 0° C. will be somewhat slow. The minimum temperature for the process of

tains the amine salt and the spent acid may be dehydrated and then recycled.

The manner of carrying out the process of this invention and the excellent results achieved therefrom will be further apparent from the following specific examples in which all parts and percentages are by weight unless otherwise specified.

EXAMPLE 1

To a well stirred mixture of 79 parts (1.0 mole) of pyridine and 112 parts (1.0 mole) of chlorobenzene there is added dropwise while cooling, 102.8 parts (1.0 mole H₂SO₄) of 95.3% sulfuric acid. A white flocculant precipitate of pyridine sulfate results. This slurry is then heated to 50° C.-55° C. and 190 parts (1 mole HNO₃) of mixed acid, containing 33% by weight HNO₃, 55% by weight H₂SO₄ and 12% water, is added slowly over a one hour period. After all the acid is in, the reaction mixture is maintained at a temperature of 50 to 55° C. for about two hours. The resulting mixture is then permitted to separate into two phases and the bottom spent acid layer is drawn off. The oil layer is washed with two aliquots containing 200 parts of water, two aliquots containing 200 parts by weight of a 5% sodium carbonate solution and finally with two additional aliquots of water. The washed oil is then heated at reduced pressure to remove any unreacted chlorobenzene and the residual water. There is obtained 49.4 parts of nitrochlorobenzene. The product contains 73% para isomer.

The following table represents additional examples of the present invention, wherein the apparatus, procedure and ingredients of Example 1 are utilized except as specified in the table. Generally, the temperature of the reaction, the reaction time and the molar ratio of nitric acid to chlorobenzene are the same as in Example 1, exceptions to this appear in the column headed "Remarks." The quantity of amine salt and the specific amine salt are varied as indicated therein and the percentage of yield is based on the monochlorobenzene charged.

Table I

Example	Amine salt	Moles amine salt per mole of chlorobenzene	Percent yield	Percent para isomer	Remarks
2	pyridine sulfate	0.25	90	67.4	Reaction time 2 hours.
3	2-picoline sulfate	0.25	90	67.8	Do.
4	quinoline sulfate	0.175	95	67.4	Reaction time 2 hours and 0.25 mole excess of HNO ₃ as mixed acid is used.
5	nicotinic acid sulfate	0.5	95	70.6	
6	t-butylamine sulfate	0.2	95	68	
7	do	1.0	96	71	
8	do	3.0	-----	70	
9	do	4.0	-----	72	
10	triethylamine sulfate	0.73	96	70	
11	trimethylamine sulfate	1.0	-----	65	

this invention is therefore that temperature just above that at which no reaction between the nitrating agent and the halobenzene will take place. The maximum temperature is only of economic importance, for it is dependent on economic factors rather than technical factors. For example, some of the aliphatic amine salts will begin to oxidize at temperatures above 100° C. and in addition, it is necessary to supply considerable amounts of heat to achieve and maintain reaction temperatures above 90° C. Temperatures within the range of from about 30° C. to about 90° C. are desirably used, while temperatures within the range of 50° C. to 60° C. are especially preferred.

After the nitration reaction is complete, the product can be recovered from the reaction by any method well known to those skilled in the art. For example, the reaction mixture is permitted to settle into two phases, i.e. an organic phase and an aqueous phase. The organic phase is then separated and the aqueous phase which con-

EXAMPLE 12

The procedure of Example 1 is repeated except that the nitration is carried out at a temperature of 15°-20° C. The para isomer content of the product is approximately 74%.

EXAMPLE 13

The procedure of Example 1 is repeated except that an equivalent amount of a mixed acid containing 36% nitric acid, 59% sulfuric acid and 5% water is used in place of the 33/55 mixed acid. The para isomer content of the product is about 73%.

EXAMPLE 14

The procedure of Example 1 is repeated except that an equivalent amount of pyridine nitrate is substituted for the pyridine sulfate of said example. Similar results are obtained in that the product contains about 70% of the para isomer of nitrochlorobenzene.

EXAMPLE 15

The procedure of Example 1 is repeated except that an equivalent amount of a mixed acid containing 27% nitric acid, 59% sulfuric acid and 14% water is substituted for the 33/55 mixed acid. The para isomer content of the product is about 70%.

EXAMPLE 16

The procedure of Example 1 is repeated using in place of the pyridine sulfate, a stoichiometrically equivalent amount of a sulfate salt of each of the following amines:

- (1) Dimethylamine
- (2) Ethylenediamine
- (3) N-ethyl-pentadecylamine
- (4) Butylamine
- (5) 1,1-dimethylpropylamine
- (6) 1,1-dimethylbutylamine
- (7) 1,1-dimethylpentylamine
- (8) Cyclohexylamine
- (9) N,N-diethylcyclohexylamine
- (10) 2,6-dimethylcyclohexylamine
- (11) Dicyclohexylamine
- (12) Pyrrolidine
- (13) Imidazole
- (14) 1,2,3-triazole
- (15) 2-piperidine
- (16) 2,6-dimethylpiperidine
- (17) 5-ethyl-2-methylpiperidine
- (18) 4-methylpiperazine
- (19) 3,5-dimethylmorpholine
- (20) Morpholine
- (21) Aziridine
- (22) Thiamorpholine
- (23) Isoquinoline
- (24) Acridine
- (25) Phenanthridine
- (26) t-Dodecylamine
- (27) t-Tetradecylamine
- (28) t-Octylamine
- (29) t-Octadecylamine
- (30) t-Hexadecylamine

In each instance the para isomer content of the product is about 70%.

EXAMPLE 17

The procedure of Example 10 is repeated using in place of the triethylamine sulfate about 1 mole of the sulfate salt per mole of chlorobenzene of each of the following trialkylamines:

- (1) Tributylamine
- (2) Tripropylamine
- (3) Triisopropylamine
- (4) N-ethyl dipropylamine
- (5) N,N-diethylbutylamine

In each case the para isomer content of the product is in excess of 70%. From the results obtained it is clear that trialkylamines wherein the alkyl groups each contain from 2 to 4 carbon atoms also constitute a preferred class of amine salts to be employed in the process of this invention.

While this invention has been described with respect to certain embodiments, it is not so limited and it is to be understood that variations and modifications thereof which are obvious to those skilled in the art may be made without departing from the spirit or scope of this invention.

What is claimed is:

1. In a process for the nitration of halobenzene, the improvement which comprises carrying out the nitration in the presence of an acid salt of an amine wherein the acid portion is derived from an acid of the group consisting of nitric acid and sulfuric acid, said acid salt being present in an amount which is sufficient to produce a para directive effect.

2. A process of claim 1 wherein the nitrating agent is a mixture comprising nitric acid and sulfuric acid.
3. In a process for the mixed acid nitration of chlorobenzene, the improvement which comprises carrying out the nitration in the presence of an amine sulfate in an amount which is sufficient to produce a para directive effect.

4. A process of claim 3 wherein the amine sulfate is derived from a heterocyclic amine.

5. In a process for the mixed acid nitration of chlorobenzene, the improvement which comprises carrying out the nitration in the presence of a sulfate salt of a tertiary alkyl amine of the formula

15

wherein R is an alkyl radical having from 1 to 18 carbon atoms, said sulfate salt being present in an amount which is sufficient to produce a para directive effect.

6. In a process for the mixed acid nitration of chlorobenzene, the improvement which comprises carrying out the nitration in the presence of a sulfate salt of a trialkyl amine wherein each alkyl group has from 2 to 4 carbon atoms, said sulfate salt being present in an amount which is sufficient to produce a para directive effect.

7. A process for the production of nitrochlorobenzene which comprises reacting monochlorobenzene with a mixed acid comprising from about 30% to about 40% by weight of nitric acid and from about 65% to about 55% by weight of sulfuric acid in the presence of from about 0.5 to 2.0 moles of an aliphatic amine sulfate per mole of monochlorobenzene.

8. A process for the production of nitrochlorobenzene which comprises adding a stoichiometric quantity of a mixed acid, comprising from about 30% to about 40% by weight of nitric acid and from about 65% to about 55% by weight of sulfuric acid, to a reaction zone containing monochlorobenzene and a sulfate salt of an aliphatic amine, the quantity of amine sulfate being within the range of from about 0.5 to about 2 moles per mole of monochlorobenzene.

9. A process of claim 8 wherein the aliphatic amine sulfate is derived from a tertiary alkylamine of the formula

50

wherein R is an alkyl radical containing from 1 to 18 carbon atoms.

10. A process of claim 9 wherein the nitrating temperature is within the range of from 50° C. to 60° C.

11. A process of claim 8 wherein the amine sulfate is tertiary butylamine sulfate.

12. A process of claim 8 wherein the aliphatic amine sulfate is derived from a trialkylamine wherein each alkyl group contains from 2 to 4 carbon atoms.

13. A process of claim 11 wherein the nitrating temperature is within the range of from 50° C. to 60° C.

14. A process of claim 12 wherein the amine sulfate is triethylamine sulfate.

15. A process for the production of nitrochlorobenzene which comprises adding a stoichiometric quantity of a mixed acid comprising from about 30% to about 40% by weight of nitric acid and from about 65% to about 55% by weight of sulfuric acid to a reaction zone containing monochlorobenzene and a sulfate salt of a heterocyclic amine, the total quantity of sulfate salt being within the range of from about 0.5 to about 2 moles per mole of monochlorobenzene and maintaining the temperature within the range of from about 30° C. to about

75

90° C. throughout the nitration reaction.

16. A process of claim 14 wherein the nitrating temperature is within the range of from 50° C. to 60° C.
17. A process of claim 15 wherein the sulfate salt is pyridine sulfate.
18. A process of claim 15 wherein the sulfate salt is 5 quinoline sulfate.

19. A process of claim 15 wherein the sulfate salt is 2-picoline sulfate.
